APPARATUS FOR DISTRIBUTING SOLID
FUEL AND THE LIKE

Charles R. Barr, Pittsburgh, Pa.

Application May 1, 1942, Serial No. 441,262

4 Claims. (Cl. 110—105)

This invention relates to new and useful improvements in method of and apparatus for stoking solid fuels or for feeding lump or powdered materials over a substantially wide surface area, and the instant application is a continuation in part of an application serially numbered 357,127 filed September 17, 1940. In the aforementioned application is described a fuel stoker and method of feeding fuel wherein and whereby the fuel is fed in measured increments and by successive charges transversely of a divergent blast, whereby it is distributed uniformly over the fire bed area.

The present application deals specifically with the construction of the blast nozzles and their disposition relative to a distributor plate to effect the desired distribution of the fuel.

The invention will become more apparent from a consideration of the accompanying drawings constituting a part hereof in which like reference characters designate like parts and in which:

Fig. 1 is a vertical cross-section partially cut away of a fire box and stoker embodying the principles of this invention;

Fig. 2 a top plan view diagrammatically illustrating the distribution of the fuel over the fire box area;

Fig. 3 a view in perspective of the fire box end of the stoker feed mechanism;

Fig. 4 a vertical cross-section partially in elevation of a steam box, nozzle and valve;

Fig. 5 a front elevational view of a blast nozzle; and

Fig. 6 a top plan view of the stoker paddle, distributor plate and blast nozzle arrangement.

In the aforementioned co-pending application, the operation of the stoker is described as feeding the fuel into a divergent blast by measured fuel charges delivered successively at different points transversely of the blast.

The present application deals primarily with the stoker features and adjustability of the blast nozzles and their relation to the distributor plate and fuel to effect proper distribution throughout the fire box area.

In Fig. 1 of the drawings, the numeral 1 designates a wall of a fire box of rectangular or other shape having a grate generally designated by the numeral 2 with movable grate bars 3, the grate forming no part of the present invention.

Mounted exteriorly of the fire box and adjacent an opening 4 thereof is a stoker comprising a hopper-shaped casting 5 having a flange 6 by which it is clamped to the wall of the fire box, and having an opening 7 through which the fuel

is fed by a paddle wheel generally designated by the numeral 8 onto a distributor plate 9.

A steam box 10 is provided below the paddle wheel. The distributor plate casting 5^a is provided with openings 11, Fig. 3, through which a plurality of nozzles 12 project. Each nozzle is provided with a regulating valve 13, as shown in Fig. 1.

The structural features of the blast nozzles 12 are more clearly shown in Figs. 4 and 5 of the drawings. The nozzle itself consists of a spherical body portion 14 having a nozzle end 15 with an elongated slot or opening 16, as shown in Fig. 5. This portion is made of stainless steel to prevent corrosion and to resist the cooling effect of the blast.

The spherical body portion 14 is mounted in a union consisting of a threaded shank 17 that is screwed in a wall of the steam box 10 having a flange portion 18 with a seat 19 of the same radius as the body portion 14. The flange 18 is threaded to interact with the thread of a sleeve nut 20 having a radius 21 corresponding to that of the body portion 14, the surfaces 19 and 21, when assembled, constituting a socket portion for engaging the nozzle. By loosening the ring nut 20, the nozzle may be adjusted through a universal movement to impinge the blast directionally to the distributor plate and transversely, as shown in Fig. 6. The volume of the blast is controlled by a screw valve 22 that seats on the chamfered face 23 of shank 17, each valve being provided with a packing box 24 and a hand wheel 25.

To obtain a distribution of fuel, as shown in Fig. 2 of the drawings, that is to maintain a fire bed of substantially uniform thickness throughout the fire box area, as shown in Fig. 1, the nozzles are arranged to impinge the blast downwardly against the distributor plate 9 as shown in Fig. 1. They are also arranged to provide a divergent blast with the end nozzles projecting sideways as shown in Fig. 2, and by adjustment of the ring nut 20, the distributing effect of the blast can be set until uniform distribution is effected. Once set, the proper distribution of the fuel will be constantly maintained.

The operation of the above described paddle and nozzle arrangement is briefly as follows:

As shown in Fig. 6, there are four sets of paddles mounted on the drive shaft 26, each of which successively delivers a measured quantity of fuel, designated by the numeral 27, to the distributor plate 9. There are five blast nozzles 12 which, in proportion to the width of the pad-

idle feed mechanism, cover an area of about 5" each. The nozzle tips are directed downward against the distributor plate to impinge the blast on the plate, and the fuel as it is delivered either in powdered or lump form, or both, is entrained by the blast and carried to the fire box, as shown in Fig. 2.

As illustrated in Fig. 6, the fuel is agitated to a state of turbulence between the blasts before it is entrained by the blast. This is because of the impingement of the blast on the distributor plate. The blast of all five nozzles is turned on constantly, although the force and volume of the individual blast may be regulated by the hand wheels 26 for each blast nozzle. In this manner, all of the fuel that is delivered by the feed mechanism is projected into the fire box from one side to the other.

It is especially noted that the primary object of the invention is to subject the fuel, or other solid or powdered particles for which this feeding method may be suited, to a violent agitation or turbulence in the feeding end of the distributing mechanism, and then project it forwardly and evenly over the receiving area.

By impinging a series of blasts on the distributor plate with adjacent blast jets, so spaced as to effect an intermingling of the blasts, such a state of intermingling of the jets of air or steam engages the solid particles of materials fed to the distributor plate, and subjects it to a thorough agitation before it is projected forwardly to the receiving area. Such a directional and cooperative arrangement of blast nozzles is so effective in maintaining the materials in a state of turbulence that there is no accumulation of the material on the distributor plate.

By this method of feeding and distributing fuel particles, it does not pile up at the front or rear or the sides of the fire box and no clinkers form. Furthermore, the finer fuel particles are ignited, and some of them completely consumed before settling on the grate. No clinkers form and the fine ash is readily sifted through the movable grate bars by manipulation of the levers 28 shown in Fig. 1.

Although one embodiment of the invention has been herein illustrated and described, it will be evident to those skilled in the art that various modifications may be made in the details of construction without departing from the principles herein set forth.

I claim:

1. A materials feeding and distributing mechanism comprising a hopper, a receiving apron beneath the hopper, a plurality of blast nozzles arranged above and directed against said apron with adjacent nozzles spaced to produce continuous intermingling blast over the entire apron area, and means for feeding solid particles in measured increments successively and progressively from the one side entirely across to the other side of said apron to different areas of said blast to be entrained and projected by said blast and uniformly distributed over a relatively large receiving area.

2. A materials feeding and distributing mechanism comprising a receiving apron, a feed mechanism for progressively delivering measured increments of the material to successive transverse areas from one side entirely across to the other side of said apron, and a plurality of blast nozzles interposed between said apron and feed mechanism to continuously entrain the material passing to the apron in the blast, said nozzles being mounted for universal movement to adjust the directional application of the material.

3. Materials feeding and distributing mechanism comprising a hopper, a receiving apron beneath the hopper, a feeder consisting of a plurality of axially spaced sets of feed paddles of an aggregate width to be substantially coextensive with said apron, the paddles of each set being angularly spaced and in staggered relation to the adjacent set whereby upon rotation of the feeder only one blade of the paddle will measure off and deliver an increment of the material being fed to said apron in successive charges progressively by the adjacent sets of paddles from one side entirely across to the other side of said apron, and a plurality of laterally spaced blast nozzles disposed intermediate the hopper and receiving apron to provide a continuous intermingling blast over the entire apron area, said nozzles being mounted for adjustment vertically and laterally relative to the apron and each other.

4. Materials feeding and distributing mechanism as set forth in claim 3 in which the nozzle elements have discharge slots and have ball and socket joints for universal movement to adjust said slots relative to said apron and each other.
